UNITED STATES PATENT OFFICE.

ROY LE FOREST GILMAN, OF BRISTOL, CONNECTICUT.

PROCESS AND APPARATUS FOR HARDENING HEADING-DIES.

1,334,606.

Specification of Letters Patent. Patented Mar. 23, 1920.

Application filed July 24, 1919. Serial No. 312,927.

To all whom it may concern:

Be it known that I, ROY LE FOREST GILMAN, a citizen of the United States, residing at Bristol, in the county of Hartford and State of Connecticut, have invented certain new and useful Improvements in Processes and Apparatus for Hardening Heading-Dies, of which the following is a specification.

10 My invention relates to improvements in processes and apparatus for hardening heading dies, being primarily adapted, as shown and described below, for use with dies for making steel balls for ball bearings, and the 15 object of my improvement is to provide means for applying the water that serves as the cooling medium to the dies in the hardening process so that the hardening will be effected in a superior manner, whereby the 20 life and efficiency of the dies will be appreciably enhanced.

In the accompanying drawing:

Figure 1 is a diagrammatic view showing one arrangement of apparatus for carrying 25 out my invention and in which the die, of circular form, is positioned horizontally and the two conductors for effecting the delivery of the cooling water are positioned vertically.

30 Fig. 2 is an end elevation of the hardening chamber of apparatus arranged with the water tubes horizontal, and in the position to receive the die.

Fig. 3 is a similar view in position for use, 35 with the water directing hood swung to the upper position.

Fig. 4 is a sectional view on the line 4—4 of Fig. 2.

Fig. 5 is a sectional view on the line 5—5 40 of Fig. 3.

Fig. 6 is a plan view, on a reduced scale, of a battery of hardening units, with the parts in different positions.

Fig. 7 is a front elevation of part of the 45 same.

Fig. 8 is an end elevation of the same.

Fig. 9 is a diagrammatic view of another 50 form of apparatus for using my invention.

Fig. 10 is a sectional view showing an application of the principle involved in my invention for hardening a special piece of material having a relatively deep impression.

The die 10 shown in the drawing as one 55 form of die for which my improved process and apparatus for hardening dies are adapted is of the usual form used as a head-

ing die in the formation of balls for ball bearings and comprises a cylindrical block of appreciable thickness and diameter, has a cup 11 in the form of a semi-spherical 60 form at each end face, positioned at the ends of the axial line, of the form desired for the material to be operated upon, the die being of the double form, as usual, and the said cups or depressions 11 are connected by an 65 axially positioned passage 12, also as usual.

In the manner of carrying out my process as illustrated by the apparatus shown in Fig. 1 the die 10 is positioned horizontally, the axis being vertical, so that there is a cup 70 11 at the middle of the end face 13 at the top side and also a cup 11 at the middle of the end face 13 at the bottom. The said die 10 is heated to the critical temperature in a furnace of suitable form before being placed 75 in the position for hardening shown in Fig. 1.

After being so heated and positioned as mentioned, being supported in any suitable and proper manner, the hardening is effected 80 by means of water, and the manner of applying the said water involves certain special features that will be described.

The top and bottom end faces 13 are treated substantially alike and the cooling water 85 is conducted to the said end faces by means of similar conductors 14 of moderate bore that are positioned along the axial line of the die 10, each terminating with the inner end opposed to and adjacent the cup 11, and 90 separated from the plane of the end face 13 by a relatively small space 17.

The delivery tubes or conductors 14 are accordingly adapted to deliver the cooling water so that the portions of the die that 95 will first receive and be cooled by the water are the two cups 11, which are directly in line with the tubes 14. After the first impact of the water against the cup portion 11 of the end faces 13 the water, which is delivered under pressure, and may be at a pressure of 120 pounds, will be diverted and will spread out laterally, radially. In order to guide the water in the outward lateral flow and to insure substantially similar and 100 equally efficient results for the upper and lower faces 13 I provide on the inner end portions of the tubes 14 flat annular plate structures 16 that are spaced from the end faces 13 by a relatively shallow water space 110 17, and which structures may be provided on the peripheries each with an inwardly di-

rected flange 18 of suitable length to slightly divert the water inwardly toward the medial axial plane. The outflow passage or discharge is in the form of the annular open space 19 between the opposed edges of the flanges 18.

I find that dies that are hardened in substantially the manner indicated and described have an appreciably longer life and 10 are considerably more efficient than dies that are hardened according to the present or ordinary methods, involving holding the dies by means of tongs in a body of water.

In the apparatus shown in the figures 15 other than Fig. 1 and Fig. 9 the die 10 is placed vertically when being treated, the axis being horizontally positioned, and the other parts of the apparatus corresponding to those shown in Fig. 1 are shifted to correspond, and there are added certain features 20 that will be described.

Thus the delivery tubes 14^a are horizontal and have the water diverting or guiding plate structures 16^a mounted on the inner 25 ends thereof. Thus the water is directed horizontally so as to impinge on the cup portions 11 of the die 10 and is spread out on all sides of the axis in a radial plane.

As a structural detail, the two plate structures 16^a are connected together by a plurality of cross connecting members 20 so as to form a cradle structure of suitable form for receiving and supporting the die 10 in proper position for being operated upon, and 30 on the inner faces of the said plate structures are mounted a plurality of inwardly projecting lug devices 21, opposed to the end faces 13 of the die 10, for providing the proper space for the water discharge at the 35 ends of the die. The upper portion 22 of the cradle structure described is open to provide a mouth for admitting the die.

As an auxiliary guide for the water discharge I inclose the structure described in 45 a hood 23 the walls of which are in spaced relation to the said structure so as to provide on all sides a passage of ample capacity for the delivery of the water discharge, the said hood 23 having an outlet 24 in the side wall that in the position for use is at the bottom 50 position so as to deliver the discharge downwardly and away from the apparatus.

Thus in the position for use the outlet 24 of the hood 23 is in registration with the 55 open space 19^a between the opposed flange structures 18^a on the lower edge portions of the end plates 16^a and on the upper side there is opposed to the open space 19^b between the flange structures 18^b a plate-like wall structure 25 that is part of the 60 peripheral wall of the hood 23.

The flange structures 18^a on the lower side are relatively long and extend inwardly appreciably, so that the open discharge space 65 19^a therebetween is relatively reduced, so as

to direct the flow of the cooling or quenching water or other liquid inwardly over the corners of the die and this particular form of structure is continued from the said lower side upwardly on each side equally so that 70 the total extent for the reduced discharge space is approximately one half of the circumference.

The flange structures 18^b on the upper side are relatively short so that the open space 75 19^b is such as to admit the die therethrough. I find, however, that by positioning the exterior plate or outer wall 25 close to the edges of the end plates 16^a so as to restrict the space 26 therebetween a compensating effect 80 is produced to compensate for the effect of the relatively wide opening 19^b so as to direct the cooling medium over the corners of the die 10 efficiently on the upper side of the said die 10.

In order to admit the die to the cradle structure the hood 23 is swung so that the outlet 24 is on the upper side and in order that this can be done the hood 23 is pivotally mounted on the supply pipes. As 90 shown, the end walls 27 of the hood 23 have holes 28 the walls of which serve as bearings that are journaled on the opposed portion 29 of the pipes 14^a. The hood 23 is swung so that the discharge outlet 24 is in 95 registration with the passage 19^a on the upper side for admitting the die, and is swung to the operating position after the die is in place.

The device described may be used alone, as 100 a single unit, or a plurality of such units may be arranged to be manipulated by a single operator, with the different units in different stages of operation, as may be convenient.

In the structure shown in Fig. 5 the end plate 16^a is screwed on to the threaded inner end of the tube 14^a and a lock nut 30 serves to position these parts, and a spacing tube 31 on the tube 14^a serves as a spacer for the 110 end wall 27 of the hood 23 relatively to the end plate 16^a.

Also, the hood 23 is made up of two mating main parts 32 that are of proper size and shape to coöperate to form the complete 115 hood structure, and these are held together by a binding plate 33 at the middle of the structure that overlaps the opposed edge portions 34 of the said main parts 32 and are secured thereto by the holding screws 35. 120

In Fig. 6 there are shown four of the units such as described and which are designated as a whole by the character 36. The two supply pipes 14^b for each unit 36 support by a journal connection the hood structure 23^b and are connected in Y-form to the single branch supply pipe 37 the flow in which is controlled by the cock 38.

The branch pipes 37 extend rearwardly to the header 39 which serves as a mechani- 130

cal support for the hardening unit in co-operation with the top edge 40 of the front wall 41 of the water tank which receives and supports the portion 42 of the branch pipe 5 37 that is intermediate the cock 38 and the junction with the header 39.

The hood 23^b in the first unit 36 toward the left is shown in the open position, the cross pieces 20^b that serve as the supports 10 for the die being exposed, and, as shown, are three in number.

In the construction described means are provided for the delivery of a stream of water or other quenching fluid or liquid directly into the impression in the die, as shown, and such or similar means may be used for operating upon any particular part of any block such as may require maximum hardening. Following upon such delivery 20 of the cooling medium is the guidance thereof over all or any parts of the die or block as may be desired by means of a suitable jacket structure.

Thus the dies may be of different forms 25 and shapes and the jacket structure would be modified to correspond.

Irregular impressions, relatively large impressions, and multiple impressions or particular areas would in some cases require a 30 modification of the details in the application of my invention, and in some cases a multiple application thereof would be needed to produce the desired result.

In the battery arrangement shown in Fig. 35 6 I find it convenient to employ a handle for turning and positioning the hood 23^b and which, as shown, comprises a main part 43 in the form of a straight bar that is secured to the side or end face of the said hood by 40 screws and a second part in the form of a laterally, outwardly directed branch 45, both of which parts serve as limiting stops in certain positions of the hood. Thus in the closed and operating position the main 45 part 43 engages with the upper side of the delivery piping structure, as indicated at 46, and in the open position the lateral branch part 45 bears against the under side of the said piping structure, as indicated at 47.

50 In the apparatus described the die operated upon is of the double form, as mentioned, and in the use thereof the dies obtained are superior to those obtained by any process heretofore in use, and one reason for the superior result obtained is the fact that there is avoided the production of steam or vapor pockets on or adjacent the surfaces to be operated upon and the effective sweeping away by the liquid flow of such steam or 55 vapor as may be formed. Also, the hardening is positively controlled to correspond to the result desired.

I find, however, that in the use of the apparatus described the diminutive passage 12 60 that extends along the axis of the die and

interconnects the bottoms of the two cups or impressions 11 is essentially inactive so far as any useful result is concerned. Actually, however, I find that the said passage may have an influence on the hardening that is 70 appreciably detrimental that is overcome in another form of apparatus Fig. 9 in which the said passage is positively used for liquid flow.

Apparatus for operating in this manner 75 is shown diagrammatically in Fig. 9. It will be noted, however, that the die 10^c that is shown to be operated upon has only one face 13^c, shown as the upper face, that has a cup or impression 11^c, the die being a 80 single die, and this is the form of die to which the said apparatus is adapted to be used.

The said apparatus comprises the vertical, axially positioned delivery tube 14^c on 85 the upper side directed toward the impression 11^c, the radial or end plate part 16^c of the water jacket mounted on the lower end of the tube 14^c and opposed to the face 13^c of the die, and the flange structure 18^c 90 extending downwardly from the edges of the plate 16^c, of cylindrical form, and opposed to the periphery of the die. The flange 18^c extends downwardly for substantially the full depth of the die and the discharge is directed downwardly from the annular water passage 48 between the said flange and the die.

It will be noted, however, that besides 100 the passage on the exterior of the die for the water there is free passageway for water along the axial diminutive passage 12^c that extends from the bottom of the impression 11^c downwardly through the body portion of the die 10^c.

105 I find that a die hardened by the apparatus shown in Fig. 9 and just described and having only a single working die has about double the life of a die of the double form and hardened in the manner described above, 110 so that the choice of the method and apparatus to be used in a particular case will be determined by the particular circumstances and conditions existent in each case.

In addition to the increased life mentioned, which applies particularly to the wearing qualities in use, there is the feature of reduced breakage due to internal hardening strains, which hardening strains are reduced in number and intensity by my 115 improved process.

In the application of my improved process shown in Fig. 10 the block 10^d that has the impression 11^d that is to be hardened the tube or conductor 14^d conducts the 120 quenching liquid into the impression and the guide block 16^d that is mounted on the conductor 14^d serves as the distributor.

The impression 11^d is relatively deep and of special form, comprising, as shown, an 130

inner end portion 49 of cylindrical form and merging into the upper or outer portion 50 of semi-spherical form. The tube 14^a projects into the said inner end portion 49 and has the peripheral wall in spaced relation to the side wall thereof and the guide block 16^a has the periphery that is opposed to the outer portion 50 spaced therefrom, the character 17^a serving to represent the outlet 10 water space between the combined tube 14^a and block 16^a for the discharge of the quenching liquid admitted through the tube 14^a.

I claim as my invention:—

15. 1. The process of hardening a heading die having an impression on one face for forming material under pressure, comprising delivering a quenching liquid directly into the said impression and guiding the

discharge from the said impression laterally 20 outwardly over the surface of the said face.

2. Apparatus for hardening a heading die having an impression on one face for forming material under pressure, comprising a tube for delivering quenching liquid directly 25 into the said impression and a guide device operatively mounted on the said tube for being opposed to the said face for guiding the said liquid outwardly laterally over the said face and away from the said im- 30 pression.

3. The process of hardening a heading die having two opposite faces each of which is provided with an impression for forming material under pressure, comprising delivering a quenching liquid simultaneously directly 35 into both of the said impressions.

ROY LE FOREST GILMAN.
